ALBERT F. ALLEN, OF PROVIDENCE, RHODE ISLAND.

Letters Patent No. 68,478, dated September 3, 1867.

IMPROVEMENT IN ESCAPE-VALVE HOSE-COUPING.

The Schedule referred to in these Letters Patent and making part of the same.

TO ALL WHOM IT MAY CONCERN:

Be it known that I, ALBERT F. ALLEN, of Providence, in the county of Providence, and State of Rhode Island, have invented a new and improved Hose-Coupling; and I do hereby declare that the following is a full, clear, and exact description thereof, which will enable those skilled in the art to make and use the same, reference being had to the accompanying drawings, forming part of this specification, in which—

Figure 1 represents a side view partly in section of my improved hose-coupling.

Figure 2 is a transverse sectional view of the same, the plane of section being indicated by the line xx , fig. 1. Similar letters of reference indicate corresponding parts.

This invention relates to a new device, by which the water can be easily discharged from hose, and by which firemen will be better enabled to carry such emptied hose up ladders or along the ground or floors. The invention consists in the use of a perforated sleeve, which is fitted around the perforated cylindrical portion of a hose-coupling in such a manner that the holes in the coupling can be completely closed by the said sleeve, when the hose can be used in the ordinary manner; but when it is desired to quickly interrupt the flowing of the water in the hose without stopping the working of the engine the holes in the coupling can be at once opened by a short turn of the sleeve. The upper end of the hose will then at once be completely emptied; thereby the said hose will be lightened and can be carried with facility to any desired place. By another short turn of the sleeve the water can be conducted into the hose again when the nozzle is brought to the required place and position.

A represents the cylindrical portion of a metallic coupling of suitable construction. Its outside should be made slightly conical, tapering toward the free end of the cylinder. B is the opposite (female) portion of the coupling, which is screwed or otherwise secured to the cylinder A. The cylinder A is perforated by four, more or less, holes. C is a sleeve fitting well around the cylinder, being made somewhat conical inside in accordance with the shape of the cylinder. The sleeve has holes which correspond to those in the cylinder. It is shorter than the cylinder, the thinner end of which is provided with a screw-thread, upon which two nuts a b are arranged, by which the sleeve can be forced up toward the wider end of the cylinder to make a tight fit. It will be easily understood that by means of a wrench or otherwise the sleeve can be turned so as to close the holes in the cylinder A, or so as to open the same, the latter position being shown in the drawings. When the holes are thus opened the water will be prevented from flowing up to the nozzle, and will escape through the holes. When the holes are closed the hose will operate in the ordinary manner.

I claim as new, and desire to secure by Letters Patent—

1. So arranging a hose-coupling that the flow of water toward the nozzle can be instantly stopped or resumed without interrupting the working of the engine, substantially as and for the purpose herein shown and described.
2. The perforated sleeve C, in combination with the perforated cylinder A and nuts a and b , all made and operating substantially as and for the purpose herein shown and described.
